United States Patent Office

Des. 233,600
Patented Nov. 12, 1974

233,600

PONTOON BOAT

Dag C. G. Forssell, Manhattan Beach, and Henry J. Folson, Redondo Beach, Calif., assignors to Vector Company, Manhattan Beach, Calif.

Filed Oct. 12, 1972, Ser. No. 296,783

Term of patent 14 years

Int. Cl. D12—06

U.S. Cl. D12—62

FIG. 4

FIG. 5

FIG. 1 is a top view of a pontoon boat showing our new design;

FIG. 2 is a side view as indicated by the arrows 2—2 of FIG. 1;

FIG. 3 is a bottom view as indicated by the arrows 3—3 of FIG. 2;

FIG. 4 is a front view as indicated by the arrows 4—4 of FIG. 1; and

FIG. 5 is a rear end view as indicated by the arrows 5—5 of FIG. 1.

We claim:

The ornamental design for a pontoon boat, substantially as shown and described.
